DESIGN FOR AN AUTOMOBILE BODY TRIM MOLDING STRIP

Lester P. Caplan, St. Louis, Mo.

Application May 15, 1943, Serial No. 110,215

Term of patent 3½ years

To all whom it may concern:

Be it known that I, Lester P. Caplan, a citizen of the United States, residing at the city of St. Louis, State of Missouri, have invented a new, original, and ornamental Design for an Automobile Body Trim Molding Strip, of which the following is a specification, reference being made to the accompanying drawing, forming a part thereof, in which Figure 1 is a side elevational view of an automobile body trim molding strip showing

my new design, an automobile being indicated in dotted outline for illustrative purposes only, Figure 2 is a top plan view, and Figure 3 is an enlarged fragmentary perspective view thereof.

I claim:

The ornamental design for an automobile body trim molding strip, substantially as shown and described.

LESTER P. CAPLAN.
